CLAIM

The ornamental design for a bicycle frame, as shown and described.

DESCRIPTION

FIG. 1 is a right side elevation view of a fully assembled bicycle frame embodying my new design;
FIG. 2 is a left side elevation view thereof;
FIG. 3 is a top plan view thereof;
FIG. 4 is an exploded perspective view thereof without the rear fork component;
FIG. 5 is a front and right side perspective view thereof;
FIG. 6 is a rear and right side perspective view thereof;
FIG. 7 is a front and right side perspective view of the main horizontal tube component thereof;
FIG. 8 is a rear and left side perspective view of the main horizontal tube component thereof;
FIG. 9 is a rear and right side perspective view of the saddle column portion thereof;
FIG. 10 is a rear and right side perspective view of the rear fork component thereof;
FIG. 11 is a rear and left side perspective view of the rear fork component thereof; and,
FIG. 12 is a rear and right side perspective view of the structural cage component thereof.
